(57) CLAIM

The ornamental design for a hand bag, as shown and described.

DESCRIPTION

FIG. 1 is a perspective view of a hand bag in accordance with the present design;

FIG. 2 is another perspective view from above with the handles unclasped.

FIG. 3 is a side view thereof;

FIG. 4 is a top view thereof; and,

FIG. 5 is a bottom view thereof.

The broken lines depicting a clasp and/or zippers in FIGS. 1-4 are shown for illustration purposes only and are not part of the claimed design.
